UNITED STATES PATENT OFFICE.

ALOIS ZIMMERMANN, OF YAKIMA, WASHINGTON.

DESIGN FOR A COMBINATION REAR LIGHT AND SIGNAL FOR AUTOMOBILES.

Application filed February 27, 1922. Serial No. 917. Term of patent 3½ years.

To all whom it may concern:

Be it known that I, ALOIS ZIMMERMANN, a citizen of Germany, residing at Yakima, in the county of North Yakima and State of Washington, have invented a new, original, and ornamental Design for a Combination Rear Light and Signal for Automobiles, of which the following is a specification, reference being had to the accompanying draw-

ing, forming part thereof, and in which the figure is a perspective view of the combination light and signal for automobiles, showing my new design.

I claim:

The ornamental design for a combination rear light and signal for automobiles, as shown.

ALOIS ZIMMERMANN.
